COMBINATION STOP ACTION FOR ORGANS

John H. Wick, Highland, Ill., assignor to Wicks
Pipe Organ Co., Highland, Ill., a corporation
of Illinois

Application October 8, 1936, Serial No. 104,681

14 Claims. (Cl. 84—344)

My invention relates to improvements in a combination stop action for organs.

One of the objects of this invention is to provide an efficient and economical combination stop action for a pipe organ, especially adapted for a direct electric organ, whereby the organist can conveniently and speedily set-up, and likewise repeatedly and alternately bring into service, various stopkey combinations, from the organ bench 10 and while playing the organ.

A more particular object of this invention is to provide a mechanism for setting-up organ stopkeys in combination, which comprises improved setter means provided with lock means 15 arranged to eliminate friction between movable parts, preferably by the use of a lock member having flexible or hingedly mounted locking elements thereon, whereby a reduction is effected in the amount of electrical current required for 20 operating the same.

These and various other objects and advantages are attained with this invention, as will become apparent from the following description, taken in connection with the accompanying drawings 25 wherein my invention is shown in its preferred form, it being understood that various other arrangements and forms of construction may be adopted for carrying out the objects and purposes of this invention.

30 In the drawings:

Fig. 1 is a diagrammatic view of the electric wiring and the improved mechanism embodying my invention, applied to a pair of stopkeys set-up on a combination piston, the various parts being 35 shown in a position of rest.

Fig. 2 is a plan view of the setting mechanisms, parts being broken away and the lower magnets with connections being omitted.

Fig. 3 is a vertical cross-sectional view thereof, 40 the parts being shown at rest with the charge contact in engagement with the off contact.

Fig. 4 is a detail front elevational view, showing a pair of trace bar magnets and a pair of piston magnets mounted below the same.

45 Fig. 5 is a vertical sectional view, taken along line 5—5 of Fig. 3.

Fig. 6 is a partial vertical cross-sectional view, similar to Fig. 3, but showing the charge contact locked or held by the locking plate, in its operative position in engagement with the on contact.

Fig. 7 is a partial vertical sectional view similar to Fig. 6, but showing the charge contact swinging the lock plate forwardly, to pass beyond the same, toward the locked or operative position 55 shown in Fig. 6.

This invention briefly pertains to the type of pipe organ provided with several combination pistons, by each of which the organist is enabled to operate a certain group or number of stopkeys simultaneously, without operating each 5 one individually. The master piston is associated with several combination pistons, and it is depressed when the stopkeys desired in a selected combination have been drawn or moved into the on position, and the combination piston is then 10 also pressed whereon said stopkeys are being set-up. After thus setting-up the desired stopkeys on the particular combination piston, the two pistons are released, and the drawn stopkeys are returned to their released or off position. 15

Thereafter, every time this combination piston is pressed, the combination of stopkeys set-up thereon is automatically operated.

My invention is an improvement over such combination stop actions, and in the drawings, by 20 way of example, two stopkeys 11 and 11' are shown, being illustrated in connection with one of the combination pistons 12 and the means whereby said stopkeys are set-up on this piston, to be operated thereby.

Other combination pistons as indicated at 12a, 25 are similarly arranged and adapted to have a group of stopkeys set-up thereon.

The stopkeys 11 and 11' are provided with actuating units 14 and 14', substantially as indicated 30 in Fig. 1 of the drawings. Each of said units includes an off magnet 15 and an on magnet 16 mounted on magnet bar 17. An armature bar 18 is pivotally mounted on bar 17, extends between said magnets, and carries on its outer end a pair of 35 oppositely extending curved arms 19 and 20, adapted to be attracted by cores 21 and 22 of said magnets 15 and 16, respectively. A rod 23 is pivotally connected to a finger 24 on said armature and to an arm 25 on the stopkey, adapted 40 to move the stopkey to the on or the off position.

These parts are shown in the off position or position of rest in Fig. 1 of the drawings; and the stopkey and armature are also indicated by dotted lines in the on position. The stopkey actuating 45 unit 14' comprises elements like those of the unit 14, being denoted by the same numbers with the prime (') mark added thereto.

When the stopkey 11 is drawn or moved from the full line position to the dotted line position 50 of Fig. 1, arm 25 and rod 23 move finger 24, which in turn brings the movable switch contact 27 into engagement with the stationary switch contacts 28 and 29 of this switch unit. Said contact 28 of this switch, and similarly contact 28' of the 55

switch for stopkey 11', are connected with the organ stop circuits 30 and 30', respectively, as indicated in said Fig. 1.

A setter switch unit is provided which is active in setting-up a combination of stopkeys on the piston 12. The unit comprises a magnet 31 which is supported and grounded with its core 32 on a metal bracket 33, and an armature bar 34 extends from the bracket, having a curved arm 35 adapted to be attracted by and movable across said core 32. A main bar 36 is pivotally connected to armature bar 34 and carries movable contacts 37, 38, 39, and 39' thereon, cooperating respectively with stationary contacts 41, 42, 43, and 43'. The movable contacts 39 and 39' are connected respectively by wires 44 and 44' with the stationary contacts 29 and 29' of the stopkey actuating units 14 and 14'; and the switch contacts 37 and 42 are connected by wires 45 and 46 with the stationary contacts 47 and 48 of the combination switch of piston 12, said contacts being engaged by a movable contact 49, and the switch closed upon pressing the piston.

Combination piston 12a is similarly provided with stationary switch contacts 47a and 48a and with a movable contact 49a for closing the switch, and is similarly equipped and connected with a plurality of stop keys adapted to be set-up thereon, as will be understood without duplicating the illustration.

A master piston or toe piston 50 is provided, which is depressed to engage its movable contact 51 with its stationary contact 52. A wire 53 extends from contact 51 to a source of power 54, for example, a generator, from which a wire 55 leads to the bracket 33 of magnet 31, and a wire 56 with a branch 56' connects said wire 55 with magnet bars 17 and 17', respectively; while a wire 57 extends from wire 53 to contact 27, having a branch 57' extending to contact 27'. A wire 58 leads from contact 52 to the coil winding of said magnet 31. By depressing the toe piston 50 the circuit thru the magnet 31 is completed, current flowing from source of power 54 thru wire 53, contacts 51 and 52, wire 58, magnet 31, bracket 33, and thru wire 55 back to the source of power 54, thereby energizing this magnet to throw these setter switches.

A combination setting and retaining mechanism is furthermore provided, which cooperates with the setter switch unit and is brought into service in setting-up and retaining the stopkeys combined on the piston. This includes a combination switch 60, a switch moving unit 61, and a switch locking unit 62. There is such a combination switch 60 and a switch moving unit 61 provided for each stopkey; while a locking unit 62 is provided for each combination piston 12, and it includes a group of locking elements for cooperation with a group of combination switches, each element cooperating with a combination switch to retain it set.

As best shown in Fig. 3, the combination switch 60 includes an off contact 63 and an on contact 64, also a charge contact 65 extending between the two, and adapted to be brought into engagement with either one thereof. The off contact 63 is connected by a wire 67 with the off magnet 15, and the on contact 64 is connected by a wire 68 with the on magnet 16. Said switch is mounted with suitable insulation on a bar 69 supported on a main frame or frame means 70.

The contact moving unit 61 includes a trace bar 71 having a slot 72, thru which extends a screw 73 arising from a supporting bar 74 which

is supported on frame means 70. Said trace bar has openings 75 and 75a, wherethru extend the contacts 65 and 65a of combination switches 60 and 60a, to be moved forwardly and rearwardly into the on and the off positions. A trace bar 78 is mounted by its core 77 on a bracket 78 which is adjustably mounted by a slot and screw means 80 on a metal cross-bar 81. (See Fig. 4.) An armature 82 is pivoted on bracket 78 and its bent end 83 is attracted by magnet core 77, while a rod 84 on the armature is connected to trace bar 71 to move it and the several switch contacts 65, 65a, forwardly from the off position, as shown in Figs. 1 to 5, to the on position as shown in Figs. 6 and 7. A spring 85 is connected to bracket 78 and to armature 82, adapted to return the latter and the trace bar to the off position.

As best shown in Figs. 2 and 3, there are several switch contacts, 65, 65a, in a row, which are moved by said trace bar 71 of unit 61, each one of said contacts and the associated stopkeys being adapted to be set-up on different combination pistons, 12, 12a, etc., so as to be inclusive with stopkeys 11' and contacts 65' of other rows, in several different combinations.

The switch locking unit 62 includes a lockbar 87 which extends across the several switch moving units 61, 61', as best shown in Fig. 2 and diagrammatically indicated in Fig. 1. Said bar has a plurality of notches 88, 88', etc. provided therein, and across the front of each of said notches is mounted a flexible lockbar plate, 89, 89', etc., each plate being swingably mounted on the bar, preferably by a pair of pins 90 secured on the bar and extending thru enlarged openings provided in the plate, whereby the plate is hingedly or swingably mounted on the bar, forwardly of the opening, and is adapted to yield when a switch contact 65 is drawn forwardly thru the notch 88 toward its locking position. The lockbar is mounted on a shaft 91, being positioned forwardly thereof, and said shaft is rotatably supported on brackets 92 which are adjustably mounted on frame means 70, by slot and screw means 92', for example, as indicated in Fig. 2.

This flexible and swingable arrangement of the locking plates enables each one of the plates 89, 89a, etc., in a row to yield readily when the trace bar 71 is drawn forwardly by magnet 76 pulling the row of contacts 65, 65a, etc., against said plates, while moving into the on position. The particular plate 89, by operation of its lockbar 87, can then be readily drawn upward or raised above the particular switch contact 65 of the selected combination, as indicated in Fig. 7, without creating any appreciable friction, to be thereafter dropped back of said contact, as shown in Fig. 6.

This locking unit 62 is operated by a lock bar magnet 93 which is mounted with its core 94 on a bracket 95 secured on a bar 96 supported on frame means 70, while the armature bar 97 is pivoted on the bracket 95 and has a bent end 98 movable across the magnet core 94. A rod 99 is pivotally connected to the armature bar 97 and to an arm 100 arising from the shaft 91, whereby said shaft is rotated when the magnet is energized. A spring 101 is connected to said armature bar 97 and to a plate 102 which is adjustably mounted by slot and screw means 103 upon bar 96 on frame means 70, thus providing for adjusting the tension of the spring. The lockbar 87 is thereby automatically returned to its off position when magnet 93 is de-energized, and a stop bracket 104 with suitable cushioning means limits

the movement of armature bar 97 to the off position.

It should be noted that in this illustrated construction the electromagnets have their negative lines connected to the steel frame of the mechanism, since the coil winding of each magnet is grounded on the core, and the core is mounted on the steel frame. This arrangement requires only one wire extending from each coil, as indicated in the drawings, and it eliminates the necessity of running a second wire to each coil.

The trace bar moving magnet 76 has its coil winding connected by a wire 105 to contact 43 of the setter switch unit; and magnet 76' is similarly connected by a wire 105' with the switch contact 43'. A wire 106 connects the metal cross bar 81 electrically with wire 55 which leads to the source of power 54.

The locking unit 62 has its magnet supporting bracket 95 connected by a wire 107 with wire 55 leading to source of power 54. The coil winding of magnet 93 is connected by a wire 108 with contact 38 of the setter switch unit.

The other contact moving units 61' are like unit 61, comprising similar members correspondingly numbered, each unit including the magnet 76' on bracket 78' grounded on said metal cross bar 81, like bracket 76; also including the trace bar 71' moved by armature 82', as best shown in Figs. 1 and 2.

The other combination switches 60' are like switch 60, each comprising contacts 63' and 64', and the movable contact 65' positioned therebetween and movable by its trace bar 71'. Wires 67' and 68' connect said contacts 63' and 64', respectively, with magnet 15' and 16' of the actuating means of stopkey 111.

A combination operating unit 110 is provided which is brought into service when the combination piston 12 is depressed for operating the stop combination on said piston. This operating unit includes an operating magnet 111 provided with a core 112 whereby it is mounted on a bracket 113 which is secured on the metal cross bar 81. An armature 114 for said magnet is pivoted on the bracket and its bent end 115 is attracted by the magnet core 112.

These operating magnets 111 are mounted with their brackets 113 on metal cross bar 81, below the trace bar moving magnets 76 with their brackets 78, both sets of magnets being grounded on said bar, substantially as indicated in the drawings.

As best shown in Figs. 5 and 6, this unit 110 also includes a roller 116 which is swingably mounted in brackets 117 supported by frame means 70, and it has a metal contact strip 118 extending longitudinally thereof and projecting from its periphery, adapted to establish contact with the several movable charge contacts 65, 65', when the roller is swung. A rod 119 is pivotally connected to an arm 120 on roller 116 and to an arm 121 on armature 114, for swinging the roller to establish the contact between said strip and said contacts. A spring 122 is connected to bracket 113 and to armature 114, for returning the latter to the off position. A contact blade 123 is supported by means 124 on frame means 70 and is adapted to make contact with said metal strip 118, and a wire 125 leads from said blade to the wire 53 which is connected to the contact 51 of the toe piston; while a wire 126 extends from the coil winding of magnet 111 to the contact 41 of the setter switch unit.

Further mechanisms are provided, of course,

for setting-up and bringing into service different groups of stopkey combinations on other combination pistons, which are operatively connected with the master piston. This is indicated in the drawings, by piston 12a with its switch contacts 47a, 48a, and 49a, the latter being shown connected with the wire 53 extending from the master switch. It is further indicated by the combination switch 60a with its contact 63a, 64a, and 65a; also by the trace bar locking unit 62a with its lockbar 87a, shaft 91a, magnet 93a, and rod 99a connecting the armature 91a with arm 100a on said shaft 91a, the roller 116a and its contact strip 118a being adapted to engage contacts 65a, the same as disclosed above.

The operation of the disclosed mechanism is as follows

The various elements and parts of the mechanism are normally in the off position or position of rest, as indicated in Figs. 1 to 5 of the drawings, but some of the stopkeys may be in their drawn or depressed position.

In order to place all depressed stopkeys associated with the combination piston 12 into the off position, the piston is pressed making contact between elements 49 and 47, whereupon the current passes from source 54 through wire 53, contacts 49 and 47, wire 45, contacts 37 and 41, wire 126, magnet 111, bracket 113, metal bar 81, wire 106, and wire 55 back to the source 54, thereby energizes said magnet and swinging strip 118 into engagement with contact 65; whereupon the current flows from the source 54 to wire 53, wire 125, contact element 123, strip 118, contact 65 and 63, wire 67, magnet 15, bracket 17, wire 56, and thru wire 55 back to source 54. The energized magnet 15 thereby draws its armature 19 and stopkeys 11 into the released or off position.

The combination of stopkeys can then be set-up on the piston. This operation involves the following steps:

First.—Draw or press down the particular stopkeys which are desired to be included in the combination on the piston 12. This brings the stopkeys in the on position and draws the armature from magnet 15 to magnet 16, thereby engaging contact 27 with 28 and 29.

Second.—Depress the master piston or toe piston 50 and hold it depressed. This engages switch contact 51 with 52, closes the circuit thru wire 52, magnet 31, bracket 33, wire 55, source of power 54, wire 53, and thru said contacts, thereby energizing magnet 31 and moving switch bar 39, separating contact 37 from 41, and engaging switch contact 38 with 42, 39 with 43, and 39' with 43'. This completes the trace bar magnet circuit, from source 54 thru wire 53, wire 57, contacts 27 and 29, wire 44, contacts 39 and 43, wire 105, magnet 76, bracket 78, metal bar 81, wire 106, and thru wire 55 back to source 54. The switch 37, 41 being open, the circuit thru the combination operating magnet 111 will be broken, thus rendering said magnet inoperative during the setting-up operation.

The energized magnet 76 actuates its armature 82 and draws trace bar 71 forward thereby drawing the associated contacts 65, 65a forwardly thru the notches 88, 88a, against the lockbar plates 89, 89a, and as said plates are flexible and swingable they will yield to enable such movements of these contacts. The contact 65, which is to be included in this combination, is thereby moved against the companion contact 64, to close

the circuit thru this combination switch to its on magnet 16.

Third.—Press the combination piston 12. This engages switch contact 49 with contacts 47 and 48, and current flows from source 54 thru wire 53, contacts 49 and 48, wire 46, contacts 42 and 38, wire 102, magnet 93, bracket 95, wire 107, and thru wire 55 back to the source 54; thereby energizing magnet 93 and drawing its armature 97 and the rod 99 to swing shaft 91 and raise the lockbar 87 and therewith the lock plates 89. This enables the raised lock plates 89, which have been flexed forwardly by the forwardly drawn contacts 65 that are associated with the depressed stopkeys, to pass over said contacts to the rear thereof.

Fourth.—Release the combination piston 12, thereby breaking the circuit thru the locking magnets 93, whereupon the lockbar 87 with its lock plates 89 drops back of the selected contacts 65 to retain them in the on position, as indicated in Fig. 6.

Fifth.—Release the toe piston or master piston 58, thereby separating switch contacts 51 and 52, and breaking the circuit thru magnet 31, whereupon switch bar 33 moves to its initial position, thereby again connecting switch contacts 37 and 41, and again separating switch contact 38 from 42, 39 from 43, and 39' from 43'. This again completes the broken path between the source of power 54 and the operating magnet.

Sixth.—Upon presssing combination piston 12, for bringing into service the stopkey combination set-up thereon, the current passes from source of power 54 thru wire 53, contacts 49 and 47, wire 45 contacts 37 and 41, wire 102, magnet 111, bracket 113, bar 31, wire 106, and thru wire 55 back to the source of power 54; thereby energizing magnet 111 and operating its armature 114 and the connected rod 119, to swing roller 118 and make contact between its strip 118 and the locked charge contacts 65, 65', etc., as well as with contact member 123. This closes the circuit from source of power 54 thru wire 53, wire 125, contact member 123, strip 118, contacts 65 and 64, wire 68, on magnet 16, magnet bar 17, wire 56, and thru wire 55 back to the source of power 54; thereby swinging the armature to the on magnet 16 and moving the stopkey into its depressed or on position. The depressing of the combination piston 12 thus brings all the stopkeys that are set-up in combination on this piston into the desired service position.

To free the stopkeys from the combination in which they have been set-up, proceed as follows:

First.—Place said stopkeys in their raised or release position, as shown in Fig. 1.

Second.—Depress the master piston 58, joining contact 51 with 52, whereupon the current flows from source 54 thru wire 53, contacts 51 and 52, wire 58, magnet 31, bracket 33, wire 55, back to source 54. The energized magnet 31 moves switch bar 33, thereby separating contact 37 from 41, and engaging contact 38 with 42, etc.

Third.—Press combination piston 12, and the current flows from source 54 thru wire 53, contacts 49 and 48, wire 46, contacts 42 and 38, wire 102, magnet 93, bracket 95, wires 107 and 55, back to source 54. The energized magnet 93 operates armature 97, rod 99 and lever 109, thereby lifting lockbar 87 with the lock plates 89, so as to fully clear the locked contacts 65, whereupon the latter snap back into their release position.

During this operation the trace bar magnet 76 is not energized to draw the trace bar 71 into locking position, since the circuit of this magnet is open, as contacts 29 and 28 are separated, as shown in Fig. 1.

While I have disclosed certain preferred embodiments of my invention, these are to be taken as illustrative only, as it is capable of change and variation to meet differing conditions and requirements, and I contemplate such modifications as come within the spirit and scope of the appended claims.

I claim:

1. A combination mechanism for an organ provided with stopkeys and actuating units therefor, said mechanism comprising a piston, a combination switch connected with each actuating unit and including a movable contact, locking means including a locking element positioned in the path of movement of each contact and being yieldable to facilitate movement of said contact toward its locking position, means operable for engaging and electrically connecting several contacts, electric means for actuating said connecting means, and circuit means including switch means associated with said electric means and with the connecting means and the piston, adapted to be closed by pressing the piston, whereby to move the stopkeys to their on position.

2. A combination mechanism for an organ provided with actuating units therefor, said mechanism comprising a combination piston, a plurality of combination switches, each being connected with an actuating unit and including a movable contact, means for drawing the contacts to the on position, locking means including locking elements which yield readily when pressed by the contacts while the latter move to the on position, thereby facilitating the withdrawing of an element from a drawn contact and the movement of the element to the rear of said contact into the locking position, and circuit and switch means operatively connected with said drawn switch contacts and with the actuating means and piston, whereby to set-up a combination of stopkeys on the piston.

3. A combination mechanism for an organ provided with stopkeys and actuating units therefor, said mechanism comprising a combination piston and a master piston, a plurality of combination switches, each being operatively connected with a stopkey actuating unit and including a movable charge contact, means operatively connected with said pistons and with the combination switches for setting-up a combination of stop-keys on the combination piston, including trace bars for engaging and moving certain charge contacts to be included, and a locking member having swingable elements which are engaged and swung by said charge contacts while the latter move to the on position, said member being adapted to move the elements into locking position on the contacts, thereby facilitating the movement of said contacts to the on position and of said elements into the locking position.

4. In mechanism for setting-up a combination of organ stopkeys and their actuating means on a piston, a plurality of combination switches, each being operatively connected to an actuating means and being under control of the piston to move the stopkey to the on and to the off positions, each switch including a movable charge contact, trace bar means having openings thru which several charge contacts extend to be moved thereby from one of said positions to the other,

locking means including locking elements yieldably mounted thereon which yield when engaged and pressed by the contacts to facilitate the latter in moving to the on position, and means 5 for moving the locking means to bring the locking elements to the rear of the contacts to retain the latter in the on position.

5. In mechanism for setting-up a combination of organ stopkeys and their actuating means on 10 a piston, a plurality of combination switches adapted to control said actuating means for moving the stopkeys to the on and to the off positions, each switch including a movable charge contact, contact moving members each engaging 15 several of said contacts to move them to their on position, lockbars having locking plates swingably mounted thereon which yield when engaged by the contacts while the latter move to the on position, and means for raising a lockbar and its 20 lock plates to clear the contacts selected for the combination, thereby facilitating the dropping of the plates in back of the contacts to retain them in the on position.

6. In mechanism for setting-up a combination 25 of organ stopkeys and their actuating means on a piston, a plurality of combination switches adapted to control said actuating means for moving the stopkeys to the on and to the off positions, each switch including a movable charge contact, trace bars, each bar having openings thru which 30 several contacts extend to be moved to the on position, lockbars having locking plates swingably mounted thereon which yield when engaged by the contacts while the latter move to the on position, and means, including a magnet to actuate 35 the lockbar also circuit means for the magnet being controlled by the piston, for raising a lockbar with its lock plates to clear the selected contacts and facilitate their return movement to drop in back of the contacts and retain them in the on position.

7. A combination mechanism for an organ 40 provided with a plurality of stopkeys and an actuating unit for each stopkey, said mechanism comprising a combination piston and a master piston operatively connected, a setter switch unit operatively connected with both pistons and including a switch for each stopkey actuating unit, said switches being closed by actuating the master 45 piston, setting and retaining means including for each stopkey a combination switch connected with an actuating unit and including a movable contact, trace means engaging several movable contacts and provided with a magnet controlled 50 by the combination piston thru one of said setter switches for moving the contacts to the on position, means for locking certain contacts in the on position and including a magnet connected thru the setter switch unit with the combination 55 piston and controlled by the latter for locking several movable contacts in the on position, to set-up a stopkey combination.

8. A combination mechanism for an organ 60 provided with a plurality of stopkeys and an actuating unit for each stopkey, said mechanism comprising a combination piston and a master piston operatively connected, a setter switch unit including a single switch connected with the combination piston and a plurality of switches, 65 one for each stopkey actuating unit, also a magnet controlled by the master piston for closing said plurality of switches, setting and retaining means including for each stopkey a combination switch which is connected with an actuating unit 70 and includes a movable contact, trace bar means

engaging several movable contacts and including a magnet controlled by the combination piston thru one of said plurality of setter switches for moving the bar means and contacts to the on position, locking means including yieldable locking elements to be engaged and moved by the moving contacts, and a magnet connected thru said single switch of the setter unit with the combination piston to be controlled thereby for locking several moved contacts in the on position, 10 to set-up a stopkey combination.

9. A combination mechanism for an organ 15 provided with a plurality of stopkeys and an actuating unit for each stopkey adapted to move it to its on and to its off positions, said mechanism comprising a combination piston having a switch, a plurality of combination switches, one being connected with each actuating unit and including a movable charge contact, means for moving said contacts to the on position, lock 20 means including lockbars each having flexible lock plates swingably mounted thereon, there being a plate for each contact adapted to be swung by the contact while moving to the on position, means controlled by the piston for moving a lock plate to clear a contact and to drop behind it in setting-up a stopkey combination on the piston, means including a metal strip movable for electrically connecting the several contacts with the piston switch, and electric means 25 operatively connected with the piston switch for moving the metal strip upon pressing the piston, to complete the circuits thru the several stopkey actuating units; whereby to set-up and to bring into service the stopkey combination. 30

10. A combination mechanism for an organ 35 provided with a plurality of stopkeys and an actuating unit for each stopkey adapted to move it to its on and to its off positions, said mechanism comprising a combination piston, a plurality of 40 combination switches, one being connected with each actuating unit and including a movable charge contact, a plurality of trace bar means and means to actuate the same, each bar means engaging a plurality of contacts for moving them 45 to the on position, lock means including lockbars each having flexible lock plates swingably mounted thereon, there being a plate for each contact adapted to be swung by the contact while moving to the on position, means controlled by the piston for moving a lockbar with its lock plates to clear the contacts and to drop behind them in setting-up a stopkey combination on the piston, means including a metal strip movable for electrically connecting the several contacts, and circuit 50 55 and switch means and a magnet controlled by the piston for moving the metal strip upon pressing the piston, to complete the circuits thru the several stopkey actuating units, whereby to set-up and to bring into service the stopkey combination. 60

11. A combination mechanism for an organ 65 provided with a plurality of stopkeys and an actuating unit for each stopkey adapted to move it to its on and to its off positions, said mechanism comprising a combination piston, a plurality of 70 combination switches, each connected with one of the actuating units and including a movable contact, means for drawing the contact to the on position, lock means including lockbars each having flexible lock plates swingably mounted thereon, each plate being yieldable when pressed by the contact in moving to its on position, means including an electromagnet controlled by the piston for raising the lock plate to its release position in setting-up a stopkey combina- 75

tion on the piston, a roller including a metal strip adapted to electrically connect the contacts, and electromagnet means charged by pressing the piston for moving the roller and metal strip 5 to complete the circuit thru the drawn contacts and associated stopkey actuating units, whereby to set-up and to bring into service the stopkey combination.

12. A combination mechanism for an organ 10 provided with stopkeys and an actuating unit for each stopkey, said mechanism comprising a combination piston provided with a switch, a combination switch for each actuating unit and including a movable contact, magnet actuated 15 means for moving each contact to the on position, locking means including a lock plate for each movable contact, the plate being swingable when engaged by said contact in moving to its on position, which facilitates moving the contact 20 and the plate to the on position, magnet actuated means for moving said locking means to the on position, a charge member with means electrically connected with the piston switch and being movable for electrically connecting the several 25 contacts with said switch, and operating means including an electromagnet connected with the piston switch for moving said charge member with its means to its operative position upon pressing the piston, whereby to complete the circuit 30 thru the several stopkey units to move the stopkeys to their on positions.

13. A combination mechanism for an organ provided with a plurality of stopkeys and actuating units therefor, said mechanism comprising a 35 combination piston and a master piston, a setter switch unit operatively connected with both pistons and including a switch for each stopkey actuating unit, setting and retaining means including for each stopkey a combination switch 40 connected with the stopkey actuating unit and including a movable contact, means including a magnet controlled by the combination piston thru one of said setter switches for moving the contact to its on position, locking means includ- 45 ing a magnet connected, thru the setter switch

unit, with the combination piston to be controlled by the piston for actuating said locking means and lock the moved contacts in the on position, means including a charge member operable to electrically connect and charge the moved contacts, and a combination operating magnet and circuit means operatively connecting it with the combination piston to operate said charge member, whereby to set-up and bring into service a stopkey combination. 5

14. A combination mechanism for an organ provided with a plurality of stopkeys and an actuating unit for each stopkey, said mechanism comprising a combination piston and a master piston, operatively connected, a setter switch unit including an operating switch and a setting switch, both connected with the combination piston, also including individual switches, one for each stopkey actuating unit, a magnet in said switch unit being controlled by the master piston, adapted to open the operating switch and to close the other switches, setting and retaining means including for each stopkey a combination switch connected with an actuating unit and having a movable contact, trace bar means including magnets, each controlled by the combination piston thru one of said individual switches, for drawing the contacts to the on position, locking means including a lockbar with yieldable lock plates engaged and swung by the moving contacts, also including a magnet connected, thru said setting switch of the setter unit, with the combination piston for actuating said lockbar with its lock plates to lock the drawn contacts in the on position, means including a charge member operable to electrically connect and charge the drawn contacts, and a combination operating unit including a magnet and circuit means connecting it, thru said operating switch of the setter unit, with the combination piston to operate said charge member, whereby to complete a circuit thru each locked contact and thru its associated stopkey actuating unit, to set-up and to bring into service the stopkey combination. 10 15 20 25 30 35 40 45
